UNITED STATES PATENT OFFICE.

MANSFIELD C. CRAWLEY, OF RUTHERFORD, NEW JERSEY, ASSIGNOR TO ADDOGRAPH COMPANY, OF LOS ANGELES, CALIFORNIA, A CORPORATION OF CALIFORNIA.

TYPEWRITING MACHINE.

Application filed February 24, 1919. Serial No. 278,872.

To all whom it may concern:

Be it known that I, MANSFIELD C. CRAWLEY, a citizen of the United States of America, and a resident of Rutherford, county of Bergen, and State of New Jersey, have invented certain new and useful Improvements in Typewriting Machines, of which the following is a specification.

The main features of this invention have relation to that type of power-driven machine disclosed in my former Patent No. 1,156,061, dated October 12, 1915, in which a spring-actuated actuator is employed for actuating the type-bars, and a continuously-driven motor is employed for pulling back and cocking the actuator after each working stroke thereof, the actuator being automatically latched back until again released by an operation of one of the character-keys. It is the special object of the present invention to adapt a ribbon frisket or vibrator mechanism for use on such machine, this mechanism being connected to the actuator in such manner that the working stroke thereof will raise the ribbon-guide to printing position, the ribbon-guide being thereafter quickly returned to normal, lower position by the act of returning or cocking the actuator-frame by the motor, as more fully hereinafter set forth.

A further object is to provide a simple color-shift mechanism for use in connection with this type of vibrator mechanism; and a still further object is to provide a simple means for adjusting the vibrating and color-shift devices to compensate for change in case, as more fully hereinafter set forth.

In the drawings—
Fig. 1 is a view partly in side elevation and partly in vertical section showing the main features of my device;

Figs. 2, 3 and 4 are views of details herein-after described;

Fig. 5 is a view partly in vertical section and partly in side elevation showing more particularly the manner of connecting the ribbon-vibrator and case-shift mechanism;

Figs. 6 and 7 are views of details herein-after more fully described;

Fig. 8 is a transverse vertical sectional view looking rearwardly to show more particularly the manner of connecting my device to the type-bar actuator.

Figs. 9, 10, 11 and 12 are views of details herein-after described.

Fig. 13 is a vertical longitudinal sectional view of a typewriting machine illustrating particularly the motor mechanism for retracting the type-bar-actuator.

In the drawings annexed, the type-bars 4 are pivotally connected in the usual manner to the type-segment 5, this segment being attached to a part 6 of the frame of the machine. Each type-bar is provided with a push-coupler 12 which is adapted to be raised into the path of the universal-actuator-bar 27 carried by the horizontal links 26 of the actuator-frame. These links 26 are pivotally attached at their forward ends to a pair of depending arms 24 carried by rock-shaft 21 journaled in frame-bars 20; and these links 26 are pivotally carried at their rear ends at the lower ends of another pair of depending arms 25 attached to a rock-shaft 22 journaled in said frame-bars 20, a spring 45 being coiled around said shaft 22 and connected at its ends to the arms 25 for the purpose of normally tending to throw the actuator forwardly to make an actuating stroke. The construction so far described is the same as in my aforesaid patent and it will be understood that a motor will be provided for retracting the actuator-frame after each actuation and also that a latching-device is employed to latch it in its returned or cocked position. A motor such as substantially shown in my aforesaid patent is shown in Fig. 13, the retracting link being shown at 18.

The two rear arms 25 of the actuator-frame are connected rigidly together at their lower ends by a bail-like bar 46 which, about midway its length, is bent upwardly to provide a vertical member 47. Pivotally attached to this vertical member 47 is the rear end of a link 48, whose forward end is pivotally attached to the depending arm of a bell-crank-lever 49, the other arm of this bell-crank being extended forwardly through a slot 50 in the frame-member 6 and having its forward end pivotally attached to the lower end of a vertically-slidable ribbon-guide 51. With this construction, it will be observed that with each working stroke of the actuator-frame the ribbon-guide will be raised to printing position and that also with each restoration of the actuator to cocked position the ribbon-guide will be positively and quickly pulled downwardly. To provide for use of this

- device on polychrome ribbons, I so connect the rear end of link 48 to the bar 47 that the pivotal point of connection may be moved closer to or farther away from the axis of movement (center of shaft 22) of said bar 47, so as to thereby vary the throw of said link 48 and consequently the height to which the ribbon-guide is raised. A convenient way of doing this is to provide the arm 47 with a longitudinal slot radially arranged with respect to the axis of the shaft 22, means being provided whereby the pivot 52 of the arm 48 may be held in its adjusted position anywhere along said slot.
- 15 To adjust and hold the pivot pin 52 in its adjusted position in its slot, I provide a vertical link 53 attached to said pivot at its upper end and pivotally connected at its lower end to the one arm 54 of the bell-crank; the other, depending, arm 55 of said bell-crank being pivotally connected to the rod 56 which extends forward to the keyboard. To push or pull the rod 56 to thus raise or lower the pivot 52, I provide a bell-crank pivotally mounted on the under surface of one of the frame-bars of the keyboard-frame, one arm 57 of this bell-crank being pivotally connected to said rod 56 and the other arm 58 being pivotally connected 30 to a link 59 which in turn is pivotally connected to a finger 60 depending through the frame-bar of the machine and carried by a rotatably-adjustable disk 61 which is adapted to be held in any one of its adjusted positions by means of a finger 62 which resiliently engages in any one of a series of notches 63 formed in the arcuate locking-plate affixed to the keyboard-frame. With this device, the ribbon-vibrating mechanism 35 may be readily adjusted to bring into use any one of a plurality of different colored zones in the ribbon. In some cases, as in stenciling, it is necessary to avoid entirely the raising of the ribbon into the path of the type; to satisfy this need, I make the upper end of the slot in the member 47 open, so that the pivot 52 may be raised entirely out of the slot and thus disconnected from the actuator entirely, so that movement of 40 the actuator will not be transmitted to the ribbon-guide. To steady and hold the pivot 52 and its connected parts when thus disconnected from the actuator, I provide a rigid bracket 64 on the frame of the machine, whose lower edge is provided with a notch 64' into which the pivot 52 enters when disconnected from the actuator, the side-walls of the notch serving to hold the pivot in alinement with the slot, so that 45 when again pulled downwardly by the link 53 it will enter the slot in the member 47.
- When this device is employed with that type of case-shift in which the platen is elevated, it lends itself very nicely to vertical adjustment synchronously with the eleva-
- tion of the platen. In the drawings, the numeral 65 designates the usual lifting-member of the platen-shift, this member being adapted to engage, in the usual manner, a transverse rod 66 on the platen-frame. 50 The bar 65 is guided vertically by a pin 67 carried by a stationary bracket 68, said pin working in a slot 69 formed in said bar 65. The bar 65 carries a horizontal pin 70 which works in an upwardly-and-rearwardly-inclined slot 71 formed in an arm 72 pivotally attached to the aforesaid bracket 68 at 73, said arm 72 serving at its forward end as a support for the pivot 74 of the bell-crank 49. With this construction, it will be observed that the vertical movement of the case-shift-bar 65 will be imparted to the pivot 74 which is the support for the bell-crank which vibrates the ribbon, so that the throw for which the device is adjusted will 55 be maintained in all positions of the platen, so that proper vibration of the ribbon will be brought about irrespective of case. The bracket 68 is provided with a lug 75 on which normally rests the arm 72 when the shift is in lower case.
- This application is subordinate to my later filed application Serial No. 577,361.
- The nature and scope of the invention having been thus indicated and its preferred embodiment having been specifically described, what is claimed as new is:
1. In a typewriting machine, a ribbon-vibrating mechanism embodying a rearwardly-extending push-and-pull link, a 100 spring-actuated type-bar-actuator adapted to operate said ribbon mechanism to shift its ribbon-guide to printing position upon each of its working strokes, and devices for adjustably connecting the rear end of said link to said type-bar-actuator to thereby permit the throw of the ribbon-guide to be varied.
  2. In a typewriting machine, a ribbon-vibrating mechanism, a spring-actuated type-bar actuator adapted to operate said ribbon mechanism to shift its ribbon-guide to printing position upon each of its working strokes and devices for adjustably connecting the actuator to the ribbon mechanism to vary the throw of the ribbon-guide. 110
  3. In a typewriting machine, a ribbon-vibrating mechanism, a spring-actuated type-bar actuator adapted to operate said ribbon mechanism to shift its ribbon-guide to printing position upon each of its working strokes, and a pin-and-slot connection between the ribbon mechanism and the actuator, for the purpose set forth. 115
  4. In a typewriting machine, a ribbon-vibrating mechanism, a spring-actuated type-bar actuator adapted to operate said ribbon mechanism to shift its ribbon-guide to printing position upon each of its working strokes, devices forming a pin-and-slot 120 connection between the ribbon mechanism and the actuator, for the purpose set forth. 125

adjustment between the ribbon mechanism and the actuator, and also devices for locking the parts in their adjusted position, for the purpose set forth.

5. In a typewriting machine, a ribbon-vibrating mechanism, a spring-actuated type-bar actuator adapted to operate said ribbon mechanism to shift its ribbon-guide to printing position upon each of its working strokes, a vibrating-arm, and means for adjustably connecting the ribbon mechanism along said arm to thus vary the throw of the ribbon-vibrator.

10. In a typewriting machine, a ribbon-vibrating mechanism, a spring-actuated type-bar actuator adapted to operate said ribbon mechanism to shift its ribbon-guide to printing position upon each of its working strokes, a vibrating-bar having a slot 15 open at one end, and a pin connecting the ribbon mechanism to the actuator through the medium of said slot and adapted to be adjusted along the slot to vary the throw of the ribbon-vibrator and to be moved out 20 through the open end of said slot to disconnect the ribbon mechanism from the type-bar actuator.

25. In a typewriting machine, a rockable shaft carrying a radial arm, this arm being radially slotted, the inner end of the slot being open, a ribbon-vibrating mechanism embodying a reciprocating bar, a pin for connecting the same to said slot, and means for adjusting the pin along said slot to 30 vary the throw of said arm, said pin being adapted to be moved radially inwardly out of said slot, for the purpose set forth.

35. In a typewriting machine, a rockable shaft carrying a radial arm, this arm being radially slotted, the inner end of the slot being open, a ribbon-vibrating mechanism

embodying a reciprocating bar, a pin for connecting the bar to said slot, means for adjusting the pin along said slot to vary the throw of said arm, said pin being adapted to be moved radially outwardly out of said slot, and a stationary device for engaging the ribbon mechanism when the pin is moved out of the slot to hold the pin in alinement with the slot. 45

40. In a typewriting machine, a rockable shaft carrying a radial arm, this arm being radially slotted, the inner end of the slot being open, a ribbon-vibrating mechanism embodying a reciprocating bar, a pin for connecting the bar to said slot, means for adjusting the pin along said slot to vary the throw of said bar, said pin being adapted to be moved radially inwardly out of said slot, and a stationary plate having a notch adapted to receive said pin when it is moved out of said slot to hold the pin in alinement with the slot. 50

55. In a typewriting machine, a ribbon-vibrating mechanism, a spring-actuated type-bar actuator adapted to operate said ribbon mechanism to shift its ribbon-guide to printing position upon each of its working strokes, said ribbon mechanism embodying a pivoted support, and a platen-shift 60 member having a pin-and-slot connection with said support, for the purpose set forth. 70

65. In combination, a ribbon-vibrating mechanism, a power type-bar-actuating mechanism, and means adjustably connecting the ribbon mechanism to said type-bar-actuating mechanism to cause same to operate the ribbon-vibrating mechanism. 75

This specification signed this eleventh day of February, A. D. 1919.

MANSFIELD C. CRAWLEY.
